(57) CLAIM

The ornamental design for a modular organizer, as shown and described.

DESCRIPTION

FIG. 1 is a perspective view of a modular organizer showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and

FIG. 7 is a bottom plan view thereof;

FIG. 8 is another perspective view thereof;

FIG. 9 is an exploded view thereof; and,

FIG. 10 is another exploded view in an alternate configuration.

The dashed or broken lines shown in the drawings depict portions of the modular organizer in which the design is embodied that form no part of the claimed design. The broken lines illustrating keys in FIG. 10 represent environment and form no part of the claim.
